(57) **CLAIM**

I claim the ornamental design for an integrated pet water bottle with bowl, as shown and described.

DESCRIPTION

FIG. 1 is a perspective view of an integrated pet water bottle with bowl;

FIG. 2 is a top-side view of the integrated pet water bottle with bowl;

FIG. 3 is a bottom-side view of the integrated pet water bottle with bowl;

FIG. 4 is a cap-end view of the integrated pet water bottle with bowl;

FIG. 5 is a rear-end view of the integrated pet water bottle with bowl;

FIG. 6 is a side elevation view of the integrated pet water bottle with bowl, the opposing side elevation view being identical;

FIG. 7 is a perspective view of the water bottle only;

FIG. 8 is a top-side view of the water bottle only, the opposing bottom-side view being identical;

FIG. 9 is a side elevation view of the water bottle only, the opposing side elevation view being identical;

FIG. 10 is a cap-end view of the water bottle only;

FIG. 11 is a rear-end view of the water bottle only;

FIG. 12 is a perspective view of the bowl only;

FIG. 13 is a side elevation view of the bowl only, the opposing side elevation view being identical;

FIG. 14 is a cap-end view of the bowl only;

FIG. 15 is a bottom-end view of the bowl only;

FIG. 16 is a top view of the bowl only;

FIG. 17 is a bottom-side view of the bowl only;

FIG. 18 is an exploded perspective view of the integrated pet water bottle with bowl; and,

FIG. 19 is a side cutaway view of the integrated pet water bottle with bowl.

The broken lines in FIGS. 1–4, 6–10, and 18–19 are for the purpose of illustrating that the integrated pet water bottle with bowl is typically used with a cap, however, many caps can be used and the cap forms no part of the claimed design.
